UNITED STATES PATENT OFFICE.

PATRICK J. ROACH AND DANIEL CARTER, OF TORONTO, ONTARIO, CANADA.

LIQUID METER.

1,420,752.

Specification of Letters Patent. Patented June 27, 1922.

Application filed November 17, 1919. Serial No. 338,720.

To all whom it may concern:

Be it known that we, PATRICK J. ROACH and DANIEL CARTER, British subjects, residing at the city of Toronto, in the county of 5 York and Province of Ontario, Dominion of Canada, have invented certain new and useful Improvements in Liquid Meters; and we hereby declare that the following is a full, clear, and exact description of the same.

10 This invention relates to a liquid meter comprising two corresponding measuring receptacles, each having an outlet port, alternately opened and closed by a float-moving valve connected with and actuating a rocker beam controlled by a float operated escapement lock, and an inlet port alternately opened and closed by the action of the beam.

In carrying out the invention the outlet ports are arranged at the bottom of the receptacles and preferably discharge into an outlet manifold, and their valves are hinged to the lower ends of a pair of connecting rods, the upper ends of which are hinged to the rocker beam on opposite sides of its fulcrum, the floats actuating these valves being fixed on the connecting rods near their lower ends.

Above the receptacles is an inlet manifold having an inlet port for each receptacle alternately opened and closed by a valve having a rack meshing with a segmental gear mounted on a spindle actuated by the rocker beam, and provided with an arm having at its free end a pin or roller.

35 Above each receptacle is a float chamber, having a perforated bottom through which the liquid content of the receptacle can enter it, and within each float chamber is a float bearing against or loosely connected with the long arm of an escapement lever, the short arms of these levers overlapping each other and underlying the path of the pin or roller and forming with it an escapement lock for the rocker beam.

45 Within the meter, above the inlet valve and its operating gear, is a baffle to prevent access to the internal mechanism of the meter, and above the baffle is a screen to break the force of the inflowing liquid.

50 For an understanding of the invention reference is to be had to the following description and the accompanying drawings in which:

55 Fig. 1, is a vertical sectional view of the meter,

Fig. 2, is a sectional elevational view of the meter showing the mechanism controlling the action of the valves looking at the apparatus from the opposite side to Fig. 1,

Fig. 3, is a top plan view of the meter, 60

Figs. 4 and 4^a, are side elevational views of the escapement levers, and

Fig. 5, is a detail view of one of the nuts for the floats actuating the escapement levers. 65

Like characters of reference refer to like parts throughout the specification and drawings.

The meter consists of a tank *a*, divided by a vertical partition *b* into two corresponding measuring receptacles *c*, *c'*, constructed to hold any predetermined quantity of liquid.

At the bottom of the tank is an outlet manifold *d* having an outlet port *d'* for the measuring receptacle *c*, and an outlet port *d''* for the measuring receptacle *c'*, and at the sides of the outlet ports *d'*, *d''*, are vertical guide rods *e*, extending above the manifold. The outlet ports *d'*, *d''*, are provided with outlet valves *f*, *f'*, having guideways *g* 80 embracing the guide rods *e* for the movement of the valves in a fixed path when respectively opening and closing the outlet ports. Each of the outlet valves *f*, *f'*, is provided with lugs *h*, and contained between the lugs of each of the outlet valves, is the lower end of its respective connecting rod *i*, *i'*. Passing through the lugs *h*, and connecting rods *i*, *i'*, are pins *j* by which the connecting rods and valves are hinged together. Fixed 90 on the connecting rods *i*, *i'*, near their lower ends are floats *k*, *k'*, respectively, these floats being held in position by washers *l*, the floats as shown in Fig. 1 being so positioned on the connecting rods as to clear the top of the 95 guide rods *e*, when the outlet valves are lowered to close the outlet ports. At the top of the measuring receptacles *c*, *c'*, is a lid or cover *m*, against which abuts the top of the vertical partition *b* to separate the measuring receptacle *c* from the measuring receptacle *c'*, and prevent an overflow from one receptacle into the other. Formed through the lid or cover *m* on opposite sides of the vertical partition *b*, are inlet ports *o*, *o'*, for the 100 measuring receptacles *c*, *c'*, respectively, and above the lid or cover *m* is an inlet manifold *p*, having an inlet nipple *q*, to which may be connected the duct for the inflowing liquid.

Within the inlet manifold *p*, is a slide 110

valve r for the inlet ports o, o' , and secured to or forming part of the slide valve r is a rack r' , with which meshes a segmental gear s fixed on a spindle s' , journaled in the sides 5 of the inlet manifold p .

Within the inlet manifold p is a substantially V-shaped baffle t covering the segmental gear s and rack r' , the apex of the baffle being opposed to the nipple and its 10 sides taking an inclination which will direct the liquid to the inlet ports o, o' , this baffle being intended to prevent access through the nipple q to the internal mechanism of the apparatus. The spindle s' projects beyond 15 both sides of the inlet manifold p and mounted on its projecting ends are corresponding rocker levers or beams u , the ends of which project evenly beyond the inlet manifold. Journaled in the projecting ends 20 of the rocker levers or beams u are rock shafts v, v' , and extending through these rock shafts are the upper ends of the connecting rods i, i' , these rods being secured to the rock shafts by means of set screws w .

25 By means of the rock shafts v, v' , and the pivot pins j , the outlet valves f, f' , can move vertically in a fixed path on the guide rods e , and the connecting rods i, i' , can swing laterally when following the curved path 30 taken by the rock shafts v, v' , during the movement of the rocker beam u . The lid or cover m is formed with elongated slots x, x' , for the lateral movement of the connecting rods i, i' , and encircling the connecting rods 35 and engaging the top surface of the lid or cover are apertured washers y, y' , having a sliding movement to cover the slots x, x' , when the valves f, f' , are lowered to prevent the liquid contents of the receptacles passing 40 through the slots to the upper surface of the lid or cover, and uncovering the slots x, x' , when the valves are raised, so that any liquid that may have passed to the top surface of the lid or cover can drain back 45 into the receptacles.

On the outer side of the inlet manifold is a bracket a' , having two lugs a'', a^3 , arranged on opposite sides of an imaginary line passing vertically through the axis of 50 the spindle s' . Fulcrumed to the lug a'' is the boss b' of an escapement lever comprising a locking arm b'' extending from the boss b' in the direction of the lug a^3 and a lifting arm b^3 , extending from the boss b' 55 in the opposite direction and taking an upwardly inclined direction. Fulcrumed to the lug a^3 is the boss e' of an escapement lever, comprising a locking arm e'' , extending from the boss e' in the direction of the 60 lug a'' , and a lifting arm e^3 extending from the boss e' in the opposite direction, the lifting arm e^3 also taking an upwardly inclined direction.

The escapement lever comprising the boss

b' , locking arm b'' and lifting arm b^3 , corresponds in all particulars with the escapement lever comprising the boss e' , locking arm e'' and lifting arm e^3 , and when assembled the locking arms b'', e'' , overlap. The lifting arms b^3, e^3 , are each heavier than 65 their respective locking arms b'', e'' , to tilt the locking arms b'', e'' , upwardly when the measuring receptacles c, c' , are empty and their corresponding valves f, f' , are lowered.

Fixed on the spindle s' is an arm f'' having at its free end a pin or roller f^3 to alternately engage with the free ends of the locking arms b'', e'' , as the arm f'' swings with the oscillation of the spindle s' , during the rocking of the lever or beam u . On the 70 top of the lid or cover m are two float chambers g', g'' , above the measuring receptacles c, c' , respectively, and within the float chambers g', g'' , are floats j', j'' .

For the movement of the lifting arms the 75 float chambers g', g'' , are slotted vertically as shown at l'' , these slots serving as guideways to prevent the lateral movement of the lifting arms during the rocking of the escapement levers.

90 The free ends of the lifting arms b^3, e^3 , are bifurcated as shown at m' , and the escapement floats are provided with upwardly extending stems or pins m'' , which pass between the forks of the bifurcations. The stems or pins m'' are screw threaded as shown in Fig. 1, and are provided with grooved nuts m^3 , the forks of the bifurcations m' engaging in the grooves of the nuts. This arrangement insures a positive up and 95 down movement for the free ends of the lifting levers unitedly with the floats j', j'' , and provides for the curved movement of the lifting arms when the escapement levers are 100 rocking on their fulcrums.

105 Formed through the bottom of the float chambers are apertures m^4 to permit of the liquid within the receptacles c, c' , entering the bottom of the float chambers when the receptacles are full.

110 When the receptacle c is filled the liquid enters the float chamber g' and lifts the float j' into the position shown in Fig. 1. This upward movement of the float j' raises the free end of the lifting arm b^3 and rocks the 115 escapement lever comprising the boss b' and locking and lifting arms b'', b^3 , on its fulcrum to lower the free end of the locking arm b'' below the path of the pin or roller f^3 , so that the arm f'' can then swing in the direction indicated by arrow in Fig. 1, and cause a corresponding oscillation of the spindle s' and segmental gear s for the movement of the slide valve r to close the inlet port o , and open the inlet port o' . This oscillation 120 of the arm f'' brings the pin or roller f^3 into contact with the top of the locking arm b'' , which it then holds in its lowered position to 125

maintain the lifting arm b^3 and float j'' in their raised position, the oscillation of the arm f'' , carrying the pin or roller f^3 beyond the free end of the locking arm e'' , 5 which then rises and engages it to hold the arm f'' and its related parts against reverse movement until the float j'' has been lifted to actuate the escapement lever consisting of the boss e' , locking arm e'' and lifting 10 arm e^3 . When the pin or roller f^3 is released from engagement with the end of the locking arm b'' and starts its movement in the direction indicated by arrow in Fig. 1, the float k moves upwardly into the position 15 shown in Fig. 1, and simultaneously lifts the valve f to open the outlet port d' , and the connecting rod i to raise the corresponding end of the rocker lever or beam u , the actuation of the rocker lever or beam u oscillating the spindle s' and segmental gear s , to reciprocate the slide valve r to close the inlet port o of the measuring receptacle c and open the inlet port o' of the measuring receptacle c' . The liquid can then flow 20 through the nipple q , inlet manifold p and inlet port o' to the receptacle c' .

When the liquid is flowing into the measuring receptacle c' the pin or roller f^3 remains in engagement with the end of the locking arm e'' until the liquid in the measuring receptacle c' rises to a height to enter the float chamber g'' and lift the float j'' sufficiently to lower the locking arm e'' and release the pin or roller for the oscillation 30 of the arm f'' in the opposite direction, the lever f'' then carrying the roller f^3 past the end of the locking arm b'' , which rises and holds the arm f'' and related parts against reverse movement, the roller f^3 then engaging 35 the top surface of the locking arm e'' and holding it lowered to maintain the lifting arm e^3 and float j'' in their elevated position. The float k is then free to rise and lift the outlet valve f to open the outlet 40 port d'' for the liquid within the measuring receptacle c' to flow out through the outlet manifold. The upward movement of the float k raises the corresponding end of the rocker lever or beam u , causing it to rock 45 the spindle s' and actuate the segmental gear to move the slide valve r to cover the inlet port o' and uncover the inlet port o . This movement of the rocker lever or beam u lowers the float k and valve f until the outlet 50 port d'' is closed. When the pin or roller f^3 passes beyond the end of the locking arm b'' , the float j'' can descend by gravity, and lower the free end of the lifting arm b^3 and raise the free end of the locking arm b'' to engage the pin or roller f^3 and hold it 55 against movement until the float j'' has again been lifted by the liquid within the measuring receptacle c . This action of the parts is repeated alternately with respect to the 60 measuring chambers c , c' , while the liquid 65

continues to flow in through the nipple q , the rapidity of the flow through the nipple having no influence upon the parts further than to affect their rapidity of action.

Within the nipple q is a screen q' to break 70 the force of the inflowing liquid, and within the outlet manifold b is a partition q'' centrally above the outlet q^3 to prevent the liquid from either of the measuring receptacles flowing into the other. 75

r'' represents a train of registering wheels operated by the rocking movement of the lever or beam u , which is provided with two offsets r^3 on opposite sides of the spindle s' , engaging with pins s^3 on the registering 80 wheels s' .

Having thus fully described our invention, what we claim as new and desire to secure by Letters Patent is:

1. A liquid meter comprising a measuring receptacle having an outlet port, a valve for alternately opening and closing said port, a float for operating the valve, a lock for controlling the movement of the valve, a float chamber above the measuring receptacle, and a float of approximately the same diameter as the float chamber connected to the lock therein for actuating the lock to release the same when the measuring receptacle is full. 90

2. A liquid meter comprising a plurality of measuring receptacles having outlet ports, valves therefor, floats for moving the valves to alternately open and close the ports, locks for controlling the movement of the valves, a float chamber above each measuring receptacle, a float in each float chamber and connections between said last named floats and the locks for alternately releasing the locks when their respective measuring receptacles are full. 100

3. A liquid meter comprising a plurality of measuring receptacles having inlet and outlet ports, valves for the outlet ports, floats for moving the valves to alternately open and close the ports, a valve for the inlet ports, means actuated by the opening and closing of the valves for the outlet ports to move the valve for the inlet ports, locks controlling said means, a float chamber above each measuring receptacle, and a float in each float chamber and connections to the locks for alternately actuating the locks when their respective measuring receptacles are full. 110

4. A liquid meter comprising two corresponding measuring receptacles, each having an outlet port, a rocker beam, valves controlling the outlet ports connected with the beam, floats for moving the valves to open 125 and close the ports, locks controlling the movement of the beam and valves, a float chamber above each measuring receptacle, and a float in each float chamber connected with the locks for alternately releasing the 130

locks when their respective measuring receptacles are full.

5. A liquid meter comprising two corresponding measuring receptacles having inlet and outlet ports, a rocker beam, valves controlling the outlet ports connected with the beam, floats for the valves, a valve moved by the beam to alternately cover and uncover the inlet ports, locks controlling the movement of the beam and valves, a float chamber above each measuring receptacle, and a float in each float chamber connected with the locks for alternately releasing the locks when their respective measuring receptacles are full.

6. A liquid meter comprising a plurality of measuring receptacles having inlet and outlet ports, valves for said ports, floats actuating the valves, locks controlling the actuation of the valves, a float chamber above each measuring receptacle and a float in each float chamber connected with the locks for alternately releasing the locks when their respective measuring receptacles are full to release the valves for movement to cover or uncover the ports.

7. A liquid meter comprising a plurality of measuring receptacles having inlet and outlet ports, a valve for the inlet ports and valves for the outlet ports, floats for moving the valves for the outlet ports, means actuated by the valves of the outlet ports for moving the valve for the inlet ports, locks controlling the actuation of said means, a float chamber above each measuring receptacle, and a float in each float chamber connected with the locks for alternately releasing the locks to release the valves for movement to cover or uncover the ports when their respective measuring receptacles are full.

8. A liquid meter comprising two corresponding measuring receptacles each having an outlet port, a rocker beam, a valve for each outlet port connected with the rocker beam, a float for each valve, an inlet port for each receptacle, a valve and connections for alternately opening and closing the inlet ports actuated by the movement of the beam, locks controlling the movement of the beam and valves, a float chamber above each measuring receptacle, and a float in each float chamber connected with the locks for alternately releasing the locks to release the valves for movement to cover or uncover the ports when their respective measuring receptacles are full.

9. A liquid meter comprising two corresponding measuring receptacles each having an outlet port, a rocker beam, a valve for each outlet port, a connecting rod hinged to each valve and to the rocker beam, a float for each valve within its corresponding receptacle, an inlet port for each receptacle, a valve to alter-

valve and connections for alternately opening and closing the inlet ports actuated by the movement of the beam, locks controlling the movement of the beam and valves, a float chamber above each measuring receptacle, and a float in each float chamber connected with the locks for alternately releasing the locks to release the beam and valves for movement to cover or uncover the ports when their respective measuring receptacles are full.

10. A liquid meter comprising two corresponding measuring receptacles each having an outlet port, a rocker beam, a valve for each of the outlet ports, a connecting rod hinged to each valve and to the rocker beam, a float for each connecting rod within its corresponding receptacle, an inlet port for each receptacle, a valve alternately opening and closing the inlet ports, actuated by the movement of the beam, escapement locks controlling the movement of the beam and valves comprising a pair of oppositely acting escapement levers, an oscillating member actuated by the beam and engaged by the escapement levers, and floats moved by the contents of the receptacles releasing the levers to release the oscillating member.

11. A liquid meter comprising a plurality of measuring receptacles having inlet and outlet ports, a rocker beam, a float moved valve for each of the outlet ports connected with the rocker beam, a valve for the inlet ports, a rack for said valve, and a segmental gear meshing with the rack and actuated by the rocker beam, in combination with a float actuated escapement lock controlling the movement of said beam and valves.

12. A liquid meter comprising a plurality of measuring receptacles having inlet and outlet ports, a rocker beam, a float moved valve for each of the outlet ports connected with the rocker beam, a valve for the inlet ports, a rack for said valve, and a segmental gear meshing with the rack and actuated by the rocker beam in combination with an escapement lock controlling the movement of said beam and valves comprising an oscillating member actuated by the beam, oppositely acting escapement levers engaging the oscillating member, and floats moved by the contents of the receptacles to position the levers to release the oscillating member.

13. A liquid meter comprising two corresponding measuring receptacles having inlet and outlet ports, a rocker beam, a valve for each of the outlet ports, a connecting rod hinged to each valve and to the rocker beam, a float for each connecting rod within its corresponding receptacle, a valve to alternately open and close the inlet ports, a rack for the valve, a segmental gear having a spindle on which is fixed the rocker beam,

an oscillating member mounted on said spindle, oppositely acting escapement levers engaging said member and preventing its oscillation, and floats moved by the contents of 5 the receptacles to position the levers to release the oscillating member.

14. A liquid meter comprising two corresponding measuring receptacles having inlet and outlet ports, a rocker beam, a valve 10 for each of the outlet ports, a connecting rod hinged to each valve and to the rocker beam, a float for each connecting rod within its corresponding receptacle, a valve to alternately open and close the inlet ports, 15 a rack for the valve, a segmental gear having a spindle on which is fixed the rocker beam, an oscillating member mounted on said spindle, oppositely acting escapement levers engaging said member and preventing 20 its oscillation, floats moved by the contents of the receptacles to position the levers to release the oscillating member, an inlet

manifold for the inlet ports, and a baffle within the inlet manifold covering the segmental gear and rack.

15. A liquid meter comprising two measuring receptacles adapted to alternately fill and empty, said receptacles having inlet and outlet ports, float actuated valves controlling said ports, a float chamber above each 30 measuring receptacle, a float in each chamber of approximately the same diameter as its float chamber, and locks connected with said last mentioned floats for preventing the movement of the valves during the filling 35 of the receptacles but released by the movement of the floats in the float chambers when the measuring receptacles are full.
